UNITED STATES PATENT OFFICE.

CARL EDWARD BAUER, OF HAMMOND, INDIANA, ASSIGNOR TO AMERICAN STEEL
FOUNDRIES, OF NEW YORK, N. Y., A CORPORATION OF NEW JERSEY.

BUILT-UP SIDE FRAME.

1,157,832.

Specification of Letters Patent.

Patented Oct. 26, 1915.

Application filed May 6, 1915. Serial No. 26,239.

To all whom it may concern:

Be it known that I, CARL E. BAUER, a citizen of the United States, and resident of Hammond, in the county of Lake and State 5 of Indiana, have invented certain new and useful Improvements in Built-Up Side Frames, of which the following is a specification.

My invention relates to railway car trucks 10 and has particular reference to a novel built-up side frame.

An object in the construction of side frames for car trucks is to provide a light, rigid and economical structure. The element of rigidity is best secured in a steel casting but the weight and cost are greater than in structures utilizing rolled or pressed metal elements. An object therefore is to 15 so combine certain rolled or pressed metal 20 sections as to secure the greatest efficiency for the weight.

The invention will be more readily understood by reference to the accompanying drawings, wherein,

25 Figure 1 is a side elevation of a side frame constructed in accordance with my invention; Fig. 2 is a plan view partly in section; Fig. 3 is a section on the line 3—3 of Fig. 1 and Fig. 4 is a section on the line 4—4 of 30 Fig. 1.

Referring more particularly to the drawings it will be seen that I provide a compression member H-shaped in cross section as indicated in dotted lines in Fig. 3, the top 35 flanges 10, being bent outwardly at the point above the bolster opening at which point the greatest transverse strength is needed. At points nearer the end of the compression member the flanges assume their original position while at the point above the journal boxes, as indicated in Fig. 4, the top flanges 40 10, are in a vertical position whereas the bottom flanges 11, are bent inwardly. At that point rivets 12, are passed through the 45 flanges 10, and the walls of the tension member and rivets 13, are passed through both the web and the inturned flanges 11 of the compression member and the web of the tension member. The tension member consists 50 of a commercial channel which is bent backward, into U-shape to form a web 14, vertical flanges 15, and horizontal flanges 16. This will be understood from Fig. 3, in which the original shape of the channel is

indicated in dotted lines. This results in 55 extreme strength both in vertical and horizontal directions. The same construction is used above the journal boxes except that the flanges 16, are sheared off for the reason that great transverse strength is not needed 60 at that point. The struts, as shown in Fig. 2, are likewise of H-section, the web 17, being terminated at the bottom at the point 18, and at the top at the point 19. The flanges 20, 21, of the H are continued beyond 65 the end of the web both at the top and bottom and are bent laterally and secured to the webs of the tension and compression members by suitable rivets. Wearing plates 22, may be secured to the inside faces of the 70 angular struts near the upper ends thereof. As a further reinforcement and as a brake hanger bracket I provide the triangular filler 23, located between the compression member and the upper end of each strut, this member being suitably riveted to the faces of the 75 contiguous parts. As a tie rod for the lower portion of the journal box I provide the bar 24, the ends of which are split and bent in opposite directions thereafter being secured 80 by means of rivets 25, to the web 14, of the tension member.

A side frame constructed as described will be found to be light in weight and extremely rigid; the disposition of the metal is such 85 that the greatest strength is secured by the use of a minimum weight.

I claim:

1. In a side frame, a compression member, tension member and struts, said compression member being of H-form in cross section, the flanges thereof being bent into horizontal position at a point midway of the length of the member, substantially as described. 95

2. In a side frame, the combination of a compression member, tension member and struts, said compression member being of original H-form in cross section and said tension member being of channel shape in 100 cross section, substantially as described.

3. In a side frame, the combination of compression member, tension member and struts, said compression member being of H-form in cross section and said tension 105 member being of channel form, a plurality of flanges of the compression member being bent in a horizontal position at a point mid-

way of the length thereof, substantially as described.

4. In a side frame, the combination of compression member, tension member and struts, said compression member being of H-shape in cross section, the member being positioned with its web in a horizontal position, a plurality of the flanges of said member being bent into horizontal position at a point midway of the length of the member, and certain flanges of said member at the ends thereof being inturned, substantially as described.

5. In a side frame, the combination of compression member, tension member and struts, said tension member being composed of a channel the edge portions of which are bent backward to form a deep channel having lateral flanges the ends of the compression member being seated in and rigidly secured to the web of said deep channel, substantially as described.

6. In a side frame, the combination of a compression member of original H-shape, a tension member of channel shape, and struts of H-shape, the parts being secured together

to form a rigid structure, substantially as described.

7. In a side frame, the combination of compression member, tension member, and struts, said struts being composed of H-shapes the flanges of which are longer than the web thereof, which flanges act as attaching means between the struts and the compression and tension members, substantially as described.

8. In a side frame, the combination of compression member, tension member and struts, said compression member being of H-form, a plurality of the flanges thereof being bent into horizontal position both at the middle and the ends thereof, said tension member being in the form of a deep channel having lateral flanges, substantially as described.

Signed at Hammond, Indiana, this 30th day of April, 1915.

CARL EDWARD BAUER.
